(57) **CLAIM**

The ornamental design for a container for food, as shown and described.

DESCRIPTION

FIG. 1 is a top perspective view of a container for food showing our new design;

FIG. 2 is a front elevational view thereof, the rear elevational view being a mirror image thereof;

FIG. 3 is a right side elevational view thereof, the left side elevational view being a mirror image thereof;

FIG. 4 is a top plan view thereof;

FIG. 5 is a bottom plan view thereof;

FIG. 6 is a top perspective view of a container top; shown separately for clarity of illustration;

FIG. 7 is a front elevational view thereof, the rear elevational view being a mirror image thereof;

FIG. 8 is a right side elevational view thereof, the left side elevational view being a mirror image thereof;

FIG. 9 is a top plan view thereof;

FIG. 10 is a bottom plan view thereof;

FIG. 11 is a top perspective view of a container bottom; shown separately for clarity of illustration;

FIG. 12 is a front elevational view thereof, the rear, right side and left side elevational views each being a mirror image thereof;

FIG. 13 is a top plan view thereof; and,

FIG. 14 is a bottom plan view thereof.
